UNITED STATES PATENT OFFICE

JAMES I. PAREL, OF CHEROKEE, IOWA

NOZZLE TIP AND SPREADER FOR LOCOMOTIVES

Application filed December 14, 1931. Serial No. 581,015.

This invention relates to steam locomotives and has for its object the provision of an attachment for the conventional type of steam nozzle tip, usually positioned in the lower part of the smoke stack, that will cause the exhaust steam to become evenly distributed within the confines of the smoke stack and by its passage out of the smoke stack create a maximum draft in the fire box.

10 Another object of this invention resides in the provision of a device of the character above set forth in which means of an adjustable nature is provided to the end that the device may be attached to locomotives of different types providing steam exhaust of different conditions.

15 A still further object of this invention is to provide an exhaust steam nozzle attachment for the purpose before set out that is simple in construction, easily and quickly attachable and can be manufactured at the minimum cost.

In the drawings—

20 Figure 1 is a longitudinal section of the front end of a conventional steam locomotive with the exhaust nozzle of this invention shown in elevation;

25 Figure 2 is a section taken on line 2—2 of Figure 1;

30 Figure 3 is a view in perspective of the improved attachment without the nozzle engaging collar;

35 Figure 4 is a section taken on line 4—4 of Figure 1.

40 Referring to the parts by reference numerals wherein like parts are designated by the like numerals in the several views, 10 designates a nozzle tip that is adapted to be threaded on the upper end of the exhaust nozzle 11. The steam spreading means consists of a plate 12 having fixed thereto supporting arms 13 that have their lower ends in detachable connection with the nozzle tip 10 by the means 14. Passing through

45 through the plate 12 and in threaded connection therewith is a threaded pipe or conduit 15 which in turn has the lowermost portion thereof in threaded engagement with the conical spreader 16. To retain the conduit 15 in proper adjustment in the spreader

16, a jam nut 17 is threaded on the conduit and moved into engagement with the upper face of the spreader 16. A jam nut 18 is provided to retain the conduit in its proper adjusted position by means of the engagement 55 of the nut 18 against the plate 12.

50 After the conduit is properly threaded in the spreader 16 and the spreader is locked in its proper position relative to the top of the exhaust jet by means of the threaded engagement of the conduit with the plate 12 and the engagement of the jam nut 18 with the plate, bracing bolts 19 that are threaded through the plate 12 are adjusted so as to engage the upper face of the spreader 16. This means is 60 provided to strengthen the assembly so that the chance of the spreader 16 being moved by the blasts of exhaust steam against the same will be reduced to a minimum.

55 In operation the nozzle tip 10 is made fast 70 to the top of the exhaust jet 11 and the arms 13 secured to the collar by the means 14. The spreader 16 is then adjusted to the proper position relative to the exhaust jet by the threaded engagement of the conduit 15 with the plate 12. The jam nut 18 having been 75 properly adjusted and the bolts 19 made to engage the spreader 16, the flow of exhaust steam moving out of the end of the jet 11 will encounter the spreader 16, and by means 80 of the conical shape of the spreader, the major portion thereof will be deflected outwardly while a certain smaller portion will flow through the conduit 15. Thus the exhaust steam as it leaves the exhaust jet will 85 be so spread as to fill the cross-section area of the smoke stack 20, as indicated by the arrows in Figure 1, and by the movement of this column of steam that fills the cross-section area of the stack a partial vacuum is 90 created in the front end of the smoke box with the result that an even draft is in the fire box for the obvious purpose.

95 Having thus described my invention what I claim is—

1. In combination with the exhaust nozzle of a steam locomotive of a device to evenly spread the flow of steam as it leaves said nozzle, said means comprising a vertically adjustable spreader for spreading the flow of 100

steam, and a conduit passing centrally and longitudinally through said spreader to permit a portion of the steam to pass therethrough, and thus completely fill the area of the smokestack and cause an even draft in the firebox of the locomotive.

2. An exhaust steam spreading attachment for the exhaust nozzle of a locomotive comprising a nozzle tip for attachment to the nozzle, arms carried by said collar, a spreader adjustably supported by said arms, and adjustable means engaging the top face of the spreader and out of the path of the flow of steam to brace the spreader against the impact of the flow of steam out of said nozzle.

3. An exhaust steam spreading attachment for the exhaust nozzle of a locomotive including a plate spaced from the nozzle, means passing through said plate and having a spreader on the lower end thereof, and a second means passing through said plate and engaging the top face of said spreader to brace said spreader against the impact of steam thereagainst, without impeding the flow of steam from the nozzle.

4. An exhaust steam spreading attachment for the exhaust nozzle of a steam locomotive, comprising a frame mounted on the exhaust nozzle, including a plate and arms attached to the nozzle to support the plate in spaced relation to the nozzle, a cone-shaped steam spreader adjustably carried on said plate to be positioned in vertical spaced relation to the exhaust nozzle to regulate the flow of steam out of the nozzle, a conduit passing through said spreader to permit a portion of the steam to pass therethrough, and adjustable means carried on said plate to brace the spreader against the impact of the flow of steam out of the nozzle.
